(57) **CLAIM**

The ornamental design for a rod holder, as shown and described.

DESCRIPTION

This application is related to concurrently filed, co-pending, and commonly assigned U.S. Patent Application Ser. No. 09/617,407, filed Jul. 17, 2000 entitled "Rod Holder," the disclosure of which is hereby incorporated herein by reference.

FIG. 1 is an isometric view of our new rod holder design from the front right where the mounting interface is shown for environmental purposes only and forms no part of the claimed design;

FIG. 2 is a right side elevation view thereof;

FIG. 3 is a top plan view thereof;

FIG. 4 is a front elevation view thereof;

FIG. 5 is a left side elevation view thereof;

FIG. 6 is a rear elevation view thereof; and

FIG. 7 is a bottom plan view thereof.

FIG. 8 is an isometric view from the front right of an alternative embodiment of our new rod holder design having a boot portion disposed at the front of the rod holder, the mounting interface is shown for environmental purposes only and forms no part of the claimed design;

FIG. 9 is a right side elevation view thereof;

FIG. 10 is a top plan view thereof;

FIG. 11 is a left side elevation view thereof;

FIG. 12 is a front elevation view thereof;

FIG. 13 is a rear elevation view thereof; and,

FIG. 14 is a bottom plan view thereof.
